UNITED STATES PATENT OFFICE.

JOSEPH R. DUNBECK, OF ROCHESTER, NEW YORK, ASSIGNOR TO THE SYMINGTON COMPANY, OF NEW YORK, N. Y., A CORPORATION OF MARYLAND.

MOLD-JARRING DEVICE.

Application filed November 9, 1925. Serial No. 68,018.

This invention relates to control mechanism for fluid actuated devices and more particularly to such mechanism for mold jarring devices.

5 The principal object of my invention, generally considered, is the provision of a device which effects the automatic shut off of mechanism particularly adapted for jarring molds after a predetermined number of vibrations or jars have been delivered to said molds.

An object of my invention is the provision of a control mechanism adapted for association with a fluid pressure actuated jolting device whereby a valve controlling the supply of fluid to said device is held open during the desired operation of said device by means of a latch engaging an operating handle of said valve and after a predetermined motion of 15 said device, said latch is automatically released to allow the valve to close and stop the operation of the device.

Another object of my invention is the provision of control mechanism for a fluid pressure actuated device which, when said device is put in operation, will oscillate a pivoted lever by means of a connection between said device and lever to turn a ratchet wheel step by step by means of a pawl on said lever and 20 after a predetermined number of oscillations will cause a cam portion on said ratchet wheel to move a latch to release position and permit a spring actuated operating handle on the main fluid pressure supply valve to return to 25 closed position and stop the operation of the device.

A further object of my invention is the provision of a guide adapted for use with control mechanism for fluid pressure actuated jolting devices employing a controlling ratchet wheel for affecting the speed of operation of said wheel by determining the number of teeth through which the wheel is turned at each vibration of the operating means for 30 said wheel.

40 Other objects and advantages of the invention relating to the particular arrangement and combination of the parts will become apparent as the description proceeds.

50 Referring to the drawings illustrating my invention, the scope whereof is defined by the appended claims:

Figure 1 is a side elevation of an embodiment of my invention.

Figure 2 is an end view of the embodiment 55 of my invention illustrated in Figure 1, a portion thereof being shown in section.

Figure 3 is a plan view partly in section on the line 3—3 of Figure 2.

Figure 4 is a fragmentary view of the other 60 end of the apparatus from that illustrated in Figure 2.

Figure 5 is a fragmentary sectional view 65 on the line 5—5 of Figure 1 looking in the direction of the arrows.

Figure 6 is a fragmentary elevational view 70 partly in section on the line 6—6 of Figure 5.

Ordinarily, air jolt machines or machines for jarring molds are controlled by an operator who turns on the air, admitting the same to a jolting cylinder from which it is automatically discharged, the device being permitted to operate until the operator thinks the mold is properly jolted. This invention is 75 designed to do away with the close personal supervision necessitated when not utilizing any automatic control apparatus in connection with the operation of the jolting cylinder.

Referring now to the drawings in detail, 80 like parts being designated by like reference characters, a fluid pressure supply pipe 1 is shown provided with a control valve 2. Said valve is provided on the stem thereof with an operating handle 3 for effecting the opening or closing thereof. In the embodiment illustrated, fluid pressure is admitted from any suitable source of supply (not shown) and travels from the left, as illustrated in Figure 1, through the valve 2 and from thence to the mold jarring device or cylinder 4 which effects the vibration or reciprocation of a platform or table 5 upon which may be placed molds or other objects which it is desired to jar or jolt. Any suitable means may be 85 employed for effecting the reciprocation, jarring or jolting of the platform or table 5, for example, a piston may be provided in said cylinder, as illustrated in Landon Patent No. 1,279,368 of September 17, 1918, said piston being adapted to automatically reciprocate 90 upon admission of fluid pressure to the cylinder thereof. The construction of the mold jarring device, however, not being part of my invention, except in combination with my control mechanism, is not further illustrated.

95 The control valve 2 is preferably mounted from a supporting frame 6 in any desired manner as by means of a bracket portion 7 100 105

thereof connected to the main portion of the frame 5 by bolts 8 or other connecting means. The operating handle 3 of the valve 2 is resiliently urged to closed position in any 5 desired manner, for example, by means of a helical or coil spring 9 surrounding a portion of the valve stem, engaging at opposite ends thereof a portion of the operating handle 3 and the casing of the valve 2. The operating handle 3 is held in open position by a latch or other retaining means 10, preferably engaging in a recess 11 formed on the underside of the operating handle 3. The latch 10 is preferably beveled on its upper 10 surface, as shown in Figure 1, and slideable in the U-shaped upper portion of the frame 6, being retained in its upper or locking position by means of a coil or helical spring 12 surrounding said latch 10 and engaging a collar 13 thereon. Said collar 13 may be immovably connected with the latch 10 in any desired manner as by means of pin 14 inserted through the collar and latch, as illustrated particularly in Figure 2. As will be understood from a consideration of Figure 2 particularly, the spring 12 is held in compression between the collar 13 and the horizontal portion 15 of the frame or standard 6 and urges the latch 10 to upper or locking position so 20 that the operating handle 3 may be turned counter clockwise as viewed from the top thereto from the closed position of the valve 2 where the handle 3 lies parallel to the pipe 1 to open position of the valve, as illustrated, with the beveled end of the latch 10 engaged in the recess 11 in said handle.

Additional guide means for the latch, an angular bracket 16 with its upright portion connected to the adjacent portion of the frame 6 and with its horizontal portion perforated for slidably engaging the latch 10, may be provided.

Preferably rotatably mounted on the frame or standard 6 or between said frame and adjacent frame portion 17 upon a pivot bolt 18 therebetween is a toothed or ratchet wheel 19. The lower end or base of the supporting member or frame 17 as well as the base of the frame 6 may be connected to the floor or ground in any desired manner as by means of bolts 20. The ratchet wheel 19 is intended for movement in only one direction and for that reason a dog 21 is provided pivoted upon a bracket 22 mounted on the frame 17 by means of bolts 23 or the like. Said dog 21 is preferably pivoted upon a pivot bolt or the like 24 provided on said bracket 22 and resiliently held in engagement with the teeth 25 on the ratchet wheel 19 by means of a spring 26 connected between a pin or extension 27 from the dog 21 and a similar extension 28 from the bracket 22. Because of this arrangement, the ratchet wheel 19 is allowed to rotate in only one direction, that is, clockwise, as illustrated in Figure 1.

For effecting the rotation of the ratchet wheel 19, an operating lever 29 pivoted preferably on the same pivot bolt 18 with the ratchet wheel 19, is provided. Motion is imparted to the operating lever 29 by a connecting rod or the like 30 pivoted at one end to the lever 29 by means of a pivot bolt or the like 31 and connected at the other end with the platform or table 5 which is jarred or jolted by the mold jarring device or the piston thereof. In the embodiment illustrated, the connection between the table 5 and the connecting rod 30 takes the form of an angular extension 30^a on said connecting rod underlying an edge of the table 5 and extending between said edge and a lug portion 32 so that reciprocating motion of said table is imparted to said connecting rod 30 and from thence to the operating lever 29. For guiding said connecting rod 30 and preventing its disengagement with the table 5, a guiding bracket 33 is provided. This guiding bracket 33 may be connected to the frame or standard 17 by bolts or the like 34 and formed with its end bent around the connecting rod 30, as indicated at 35, thereby properly guiding the same and preventing its disengagement from the table 5.

Pivotedly connected near the outer end of the lever 29 by means of a pivot bolt or the like 36 is a pawl 37, the operative end of which is pressed into engagement with the teeth 25 of the ratchet wheel 19 by resilient means such as the flat or leaf spring 38 mounted on said lever 29 as by means of stud 39.

It will be apparent that, on account of this construction, the pawl 37 is adapted for turning the ratchet wheel 19 in a clockwise direction upon the downward reciprocation of the table 5 but will slide over one or more of the teeth 25 of the ratchet wheel 19 upon the upward reciprocation of said table. In order to regulate the number of teeth through which the ratchet wheel 19 is turned at each reciprocation of the table 5, a guide 40 is provided adjustably mounted on the standard or frame 17 as by means of bolts 41 engaging in apertures in said guide and in corresponding apertures 42 in said standard. The upper portion of the guide 40 is formed with an edge 43 substantially coaxial with the ratchet wheel 19 and the pawl 37 is provided with a pin 44 extending laterally therefrom so as to engage and ride over the bracket 40 along the edge 43 to disengage said pawl 37 from the teeth 25 of the ratchet wheel 19 and limit the number of teeth through which the pawl 37 will turn the ratchet wheel 19 at each reciprocation of the table 5. For example, when the bracket 40 is adjusted, as illustrated in Figure 1, it will cause the pawl 37 to disengage from the teeth 25 after slipping over one tooth and thereby cause the ratchet wheel 19 to be moved only one tooth for each reciprocation of the table 5. If it were desired to

effect a more rapid operation of the ratchet wheel 19, the guide 40 would be adjusted upwardly so that disengagement between the pawl 37 and the teeth 25 would not be effected until after said pawl had slipped over more than one of said teeth 25.

In order to cushion the motion of the operating lever 29, the same is preferably extended beyond the pivot bolt 18 and a coil spring 45 provided between the same and the bracket 22, or a U-shaped portion 46 thereof. Said coil spring 45 may be positioned in compression in any desired manner between said portion 46 and the lever 29 as by being mounted on upright pin 47 on said lever and pin 48 on the U-shaped portion 46, said pin 48 preferably being threaded with respect to the U-shaped portion 46 to facilitate assembly of the spring 45 in place.

For effecting the unlocking or release of the operating handle 3, a stop or cam block 49 is formed on the ratchet wheel 19, as illustrated particularly in Figure 6. Said cam block 49 may be connected with said ratchet wheel 19 in any desired manner as by means of pins or bolts 50 and the cam or rounded edge thereof is formed near the teeth 25 or outer edge of the ratchet wheel 19 and adapted to engage a pivotally mounted cam or latch actuating member 51 upon a predetermined motion of the ratchet wheel 19. The cam 51 may be pivoted on bolt 52, which bolt may be supported in any desired manner as by extending through an aperture in the guide bracket 33 and a corresponding aperture in a bracket 53 connected to frame or standard 6 in any desired manner as by bolts 54, as illustrated particularly in Figure 5. The pivoted cam 51 is formed with an upwardly curved end portion 55 over which the portion 49 rides after a predetermined motion of the ratchet wheel 19 thereby turning said cam counter clockwise, as viewed in Figures 1 and 6, and causing the lower curved end portion 56 to engage a transverse extension 57 from the latch 10 and thereby effect the downward movement of said latch 10 to release or unlocking position. Said extension 57 in the embodiment shown passes through an aperture 58 in the frame or standard 6.

The operation of the aforesaid controlling device may be as follows. The ratchet wheel 19 is turned by hand in a clockwise direction past the dog 21 and pawl 37 until it is positioned so that the stop or cam block 49 is a given number of teeth in advance or counter clockwise beyond the pivoted cam 51 corresponding to the number of vibrations or jolts desired to be given to the platform or table 5 and the molds or other articles thereon. The guide 40 is likewise adjusted so that it permits the sliding over of one or more teeth 25 by the pawl 37 as desired in accordance with the desired speed of operation of the ratchet wheel 19. The operat-

ing handle 3 for the valve 2 is moved counter clockwise, as viewed from above, from a position where it lies along the supply pipe 1 through approximately 90° to a position illustrated in Figures 1 and 2 where it rides over the beveled edge of the latch 10 and is locked in position, by said latch engaging in the aperture or recess 11 in said operating handle 3. The opening of the valve 2 by the turning of the handle 3, as aforescribed, will effect the operation of the jolting device by admitting compressed air or fluid to the cylinder 4 and thereby cause a reciprocation or jolting of the table 5. This reciprocatory motion is transmitted to the operating lever 29 from the table 5 by means of the connecting rod 30 and through the pivot bolt 36 and pawl 37, step by step motion is imparted to the ratchet wheel 19 by the engagement of said pawl 37 with the teeth 25 thereon. When the ratchet wheel 19 has turned so that the cam block 49 thereon rides over the curved portion 55 on the pivoted cam 51, the said cam 51 is pushed downwardly thereby forcing the latch 10 through engagement with the extension 57 therefrom to release position, thereby allowing the spring 9 to return the valve and operating handle thereof to closed position and stop the operation of the mold jarring device and the reciprocation of the table 5.

It will be apparent that by virtue of the aforesaid mechanism, an operator may set the controlling ratchet wheel for the desired number of jolts, to be delivered to the mold, open the valve 2 and leave the machine to operate, as it will continue to operate only until the ratchet wheel 19 has been turned the predetermined amount when the handle 3 is automatically released and the main valve closed thereby stopping the device automatically at the desired time.

Having described my invention, what I claim is:

1. The combination with a fluid pressure actuated jolting device, of a valve controlling the supply of fluid pressure thereto, spring means tending to close said valve, means for manually opening said valve, latch means for retaining said valve open and means operated by movement of the jolting device for releasing said latch means and allowing said spring means to close the valve.

2. The combination with a fluid pressure actuated jolting device, of a valve controlling the supply of fluid pressure thereto, resilient means for normally retaining said valve closed, manual means for opening said valve, means for retaining said valve open and adjustable means actuated by motion imparted from the jolting device for releasing said retaining means and allowing said resilient means to act and close the valve.

3. The combination with a fluid pressure actuated jolting device, of a valve control-

ling the supply of fluid pressure thereto, resilient means for normally retaining said valve closed, manual means for opening said valve, means for retaining said valve open, 5 a ratchet wheel pivotally mounted adjacent said valve, means allowing turning of said wheel in only one direction, a lever pivoted adjacent said wheel, means mounted on said lever and adapted to engage said ratchet wheel and turn it in the allowed direction when the lever is moved in said direction, and slide over said ratchet wheel when the lever is moved in the opposite direction, a portion on said ratchet wheel engageable 10 with the retaining means to release said means after a predetermined movement of the ratchet wheel and a connection between the jolting device and lever for effecting movement of the ratchet wheel by oscillation 15 of the lever.

4. The combination with a fluid pressure actuated jolting device, of a valve controlling the supply of fluid pressure thereto, resilient means for normally retaining said valve closed, manual means for opening said valve, means for retaining said valve open, a ratchet wheel rotatably mounted adjacent said valve, means engaging the teeth of said wheel to permit rotation in one direction 25 only, a lever pivoted coaxially with respect to said wheel, a pawl pivoted to said lever and adapted to engage said ratchet wheel and turn it in the permitted direction when the lever is rotated in said direction and slide 30 over said wheel when the lever is rotated in the opposite direction, a cam portion on said ratchet wheel engageable with the retaining means to release the same after the pawl on the lever has moved the wheel a predetermined number of teeth, and a connection between the jolting device and lever for oscillating the lever to effect movement of the ratchet wheel for releasing the retaining means.

45 5. The combination with a fluid actuated jolting device, of a valve controlling the supply of fluid pressure thereto, a spring connected to said valve for normally retaining the same closed, an operating handle for opening said valve, a latch engaging a portion of said handle for retaining said valve open, an adjustable means actuated by motion from the jolting device for withdrawing said latch to release the handle and allow the spring to act and close the valve after a predetermined amount of motion of the jolting device.

60 6. The combination with a fluid pressure actuated jolting device, of a fluid pressure valve controlling the supply to said device, spring means associated with said valve for normally closing said valve, a latch engaging said handle for retaining said valve open, a ratchet wheel rotatably mounted near said valve, a dog engaging the teeth of said wheel

to permit rotation thereof in one direction only, a lever pivoted coaxially with respect to said wheel, a pawl pivoted to said lever and engaging said ratchet wheel for turning the same in the permitted direction when the lever is oscillated in said direction and for sliding over said wheel when the lever is oscillated in the opposite direction, a cam portion on said ratchet wheel, a pivoted cam engaged by said cam portion and provided with a portion engaging said latch for moving the same to release position when actuated by the cam portion on the wheel and a connection between the jolting device and lever for effecting the oscillation of said lever.

7. The combination with a fluid pressure actuated jolting device, with a fluid pressure valve controlling the operation of said device, a frame supporting said valve, spring means connected to said valve for turning the same to closed position, an operating handle on said valve for opening the same, said operating handle being provided with a recess, a slidable latch mounted in said frame and engaging in the recess of said handle for retaining the same in open position, resilient means for retaining said latch in locked position, a ratchet wheel rotatably mounted on said frame, a lever pivoted to said frame, a pawl pivoted to said lever and spring pressed into engagement with said wheel for turning the same in a given direction upon oscillation of said lever, a connection between said jolting device and lever for oscillating said lever, and a guide adjustably mounted on said frame for causing the pawl to turn the ratchet wheel through one or more teeth as desired at each oscillation of the jolting device.

8. The combination with a fluid actuated jolting device, of a valve controlling the supply of fluid pressure thereto, resilient means for normally retaining said valve closed, a frame for supporting said valve, manual means for opening said valve, retaining means mounted on said frame for holding the same in open position, a ratchet wheel mounted on said frame, a lever mounted on said frame and provided with a pivoted spring-pressed pawl engaging said ratchet wheel for turning the same step by step to finally cause the engagement between a portion thereof and the latch for releasing the opening handle and allowing the valve to close, a connection between said opening lever and jolting device for effecting the oscillation of said lever and resilient means between a portion of said lever and the frame for cushioning the operation of said lever.

9. Control mechanism comprising a fluid pressure valve, resilient means tending to close said valve, a handle on said valve for opening the same, a latch engaging said handle for holding the same in open position, a

ratchet wheel mounted adjacent said valve and provided with means thereon engageable with said latch for moving the same to unlocked position and means engaging the teeth of said ratchet wheel for effecting the step by step motion thereof whereby the closing of said valve is effected after a predetermined movement of the ratchet wheel.

10. Control mechanism for a fluid actuated device, comprising a valve through which fluid is conducted to said device, a spring for closing said valve, an operating handle on said valve, latch means engaging said han-

dle for holding the same in open position, a ratchet wheel mounted adjacent said valve, 15 a pivoted lever provided with a spring pressed pawl thereon engaging the teeth of said ratchet wheel, a connection between said lever and device for oscillating the same and a portion on said wheel engageable with 20 said latch to release the valve handle and allow the valve to close after a predetermined motion of the device.

In testimony whereof I affix my signature.

JOSEPH R. DUNBECK.
